CLAIM

What is claimed is an ornamental design for vented eye protection device, as shown and described.

DESCRIPTION

FIG. 1 is a front, top, left perspective view of a vented eye protection device showing my new design

FIG. 2 is a frontal elevation view with the broken line subject matter as seen in FIG. 1 removed for ease of understanding.

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The Broken lines in the drawings are shown for the purpose of illustrating portions of the vented eye protection device and form no part of the claimed design.

1 Claim, 7 Drawing Sheets
